To all whom it may concern:

Be it known that, AUGUSTA FELSHIN, a citizen of the United States, and resident of New York city, in the county of New York and State of New York, has invented a new, original, and ornamental Design for Lady's Hat or Similar Article, of which the following is a specification, reference being had to the accompanying drawings, forming part thereof, in which,

Fig. 1 is a front elevational view of a lady's hat embodying my new design; and
